[57] CLAIM

The ornamental design for flexible plug for beverage can, as shown and described.

DESCRIPTION

FIG. 1 is a perspective view of a flexible, opaque plug for a beverage can showing my new design;

FIG. 2 is a top, plan view thereof;

FIG. 3 is a side elevational view thereof;

FIG. 4 is a bottom plan view thereof;

FIG. 5 is a front elevational view thereof;

FIG. 6 is a rear elevational view thereof;

FIG. 7 is a perspective view of a flexible, transparent plug for a beverage can showing a second embodiment of that shown in FIG. 1;

FIG. 8 is a top plan view thereof;

FIG. 9 is a side elevational view thereof;

FIG. 10 is a bottom plan view thereof;

FIG. 11 is a front elevational view thereof;

FIG. 12 is a rear elevational view thereof;

FIG. 13 is a perspective view of the plug of FIG. 1 shown in operable relation with respect to a beverage can; and, FIG. 14 is an exploded perspective view of the plug of FIG. 1 shown in spaced relation to the opening formed in a beverage can.

The broken line showing of a beverage can in FIGS. 13 and 14 are for illustrative purposes only and form no part of the claimed design.
